UNITED STATES PATENT OFFICE.

FRANK A. HOWARD, OF ELIZABETH, NEW JERSEY, ASSIGNOR TO STANDARD OIL DEVELOPMENT COMPANY, A CORPORATION OF DELAWARE.

ART OF CRACKING HYDROCARBONS.

Application filed March 20, 1923. Serial No. 626,264.

This invention relates to the art of pyrolytic conversion of hydrocarbons into products of lower boiling point, and will be fully understood from the following description, 5 taken in connection with the accompanying drawing which represents semi-diagrammatically one form of apparatus contemplated in the invention.

In the Patent No. 1,415,232 to Ellis, there is 10 set forth a process in which an oil is brought up to decomposing temperature by passing through a heated zone and is then allowed to crack while passing at a slower rate through an enlarged passageway without the temperature dropping below the decomposing range. 15 The present invention is in part directed toward improvements thereon.

Referring to the drawing, the reference character 1 designates a suitable furnace 20 chamber heated by coal or oil-burners or other fuel, as preferred. A feed pipe 2 leads to a lower coil A made up as desired; for instance parallel tubes 3 joined at the adjacent ends by connections so as to give a consecutive path 25 through tube after tube and from the lower row by a connection 4 leading to an upper row of tubes 5. The number of rows provided may be as preferred, but for usual conditions two rows with the tubes in staggered positions 30 is desirable. Such arrangement quite completely presents surfaces intercepting radiant heat rays from the furnace chamber, while allowing the hot combustion gases to freely pass up beyond. From the lower coil, a pipe 6 35 leads to a vaporizing chamber or still 7. This may be of any desired form, for instance of "water-tube boiler" type, or a simple shell still. A tar draw-off pipe 8 is connected at the lowest part, and from the top of the still 40 a vapor line or pipe 9 leads to a second coil B in the furnace chamber 1. This coil may be constructed along the same general lines as the first coil and be made up of a plurality of rows of tubes 10 according to the capacity 45 desired, the spacing of the tubes being such as to allow a good exposure to the combustion gases on their way to the exit flues F. From this upper coil a discharge pipe 11 leads to an enlarged passageway or drum 12, which may 50 conveniently be placed in the top of the same furnace-setting and lagged or heat-insulated on top, so as to maintain the temperature desired. The drum may, however, be set in any other way desired, so long as it is prepared

to maintain the temperature of its contents 55 without substantial decline.

From the enlarged passageway or drum 12 a vapor line or pipe 13 leads, preferably with a slight downward gradient, to a suitable rectifying device 14, which may be a dephlegmator or fractionating tower as desired. A vapor line 15 from the top of the rectifier 14 connects, through a suitable cooled condenser 15', with a receiving drum 16, having valve-controlled drain-line 17 and gas-release 60 18 as usual. A pipe 19 with pump 20 connects the lower part of the receiving tank with the upper part of the rectifier, for a purpose to be referred to later, and a reflux-pipe 21, with a pump 22 where necessary, leads 65 from the lower part of the rectifier back to the still 7.

In carrying out my process, the oil to be cracked is fed into the system by pipe 2. Advantageously such oil may be a crude from 75 which the light constituents have been removed. Passing through the lower coil A, the oil is discharged into the still 7, having been heated sufficiently to allow substantial vaporization of the constituents desired. 80 Such additional heat as is necessary to effect the degree of vaporization wanted is provided by firing the still 7 in the usual manner. In this still it is the aim to take off the constituents most suitable for cracking, these being forwarded in vapor form to the coil B. 85 The distillation is thus carried to a low percentage pitch bottom, as heavy as can be handled, the bottoms or residue being drawn off, continuously or intermittently as desired, 90 through the tar line 8. In this way, oils of any practicable content of crackable constituents may be efficiently handled, irrespective of asphalt or coke-forming contents, such materials being separated from the crackable 95 constituents and eliminated before the cracking stage, and by eliminating such materials serious coke troubles in the cracking operation are avoided. The pressure in the still 7 may be as low as is consistent with a good 100 delivery rate of vapors on through the coil B, and depending upon the stock operated upon may in general lie between 5 and 150 pounds per square inch. As indicated, the vapors proceed to the coil B and passing there-through are raised to a temperature of 105 875°—975° F. The position of this coil B is such that it is shielded by the lower coil

A, the coil A in fact being designed as a screen interposed between the coil B and the furnace, to protect coil B against the radiant heat of the furnace. The coil A handling the feed oil at an adequate velocity on its way to the still 7 absorbs the radiant heat, it being harmlessly directed to raising the temperature of and partly vaporizing the oil on its way to the still. The heat effective on the coil B is thus limited to the mild and relatively uniform heat of the combustion gases.

Entering the drum 12 from the coil B, the vapors are passed along at a suitable rate, the inlet preferably being arranged at one end and the outlet at the opposite end, and the temperature being maintained in general at 825°—950° F., a yield of 15—30% of gasoline may be directly obtained.

The pressure in the drum 12 does not need to be high, only sufficient to maintain a suitable throughput, and may be for instance from 15 up to 150 pounds per square inch.

From the drum 12, the vapors proceed to the rectifier 14 where the gasoline constituents are sorted out and forwarded to the condenser 15 and receiving drum 16. To facilitate such rectification, condensate is drawn off from the receiver 16 and is forced by the pump 20 into the upper part of the rectifier and passing down countercurrent to the vapor, washes and fractionates it. The heavy reflux from the bottom of the rectifier, also that draining down from the vapor line 13 by reason of its downward slope, is returned through a suitable trap 23 and pipe 21 to the still 7 for recycling. Where desired, instead of returning the heavy condensate from the vapor line 13 to the still as mentioned, it may instead be drawn off aside by a pipe 24.

While I have described my invention by reference to certain specific details, it will be understood that this is for the purpose of making the invention clear, and is not limitative. And the invention is to be considered as limited only as defined in the following claims, in which it is my intention to claim all inherent novelty as broadly as the prior art permits.

What I claim is:

1. Apparatus of the character described, which comprises a furnace, a heating coil in said furnace located as a screen to absorb radiant heat, a distillation chamber into which said coil discharges, another heating coil in said furnace screened by the first-mentioned coil and receiving vapors from the distillation chamber, an enlarged passageway into which the last-mentioned coil discharges, means for maintaining the temperature in the enlarged passageway without substantial decline, a vapor line leading from said enlarged passageway and having a downward slope therefrom, a rectifier for the vapors, a vapor line from the top of said rectifier, a condenser on said vapor line, a

tank for receiving condensate, means for returning condensate from said tank into the top of the rectifier, and means for returning reflux from the bottom of the rectifier to the distillation chamber.

2. Apparatus of the character described, which comprises a furnace, a heating coil in said furnace located as a screen to absorb radiant heat, a distillation chamber into which said coil discharges, another heating coil in said furnace screened by the first-mentioned coil and receiving vapors from the distillation chamber, an enlarged passageway into which the last-mentioned coil discharges, means for maintaining the temperature in the enlarged passageway without substantial decline, a vapor line leading from said enlarged passageway and having a downward slope therefrom, a rectifier for the vapors, a vapor line from the top of said rectifier, a condenser on said vapor line, and means for returning condensate into the top of the rectifier.

3. Apparatus of the character described, which comprises a furnace, a heating coil in said furnace located as a screen to absorb radiant heat, a distillation chamber into which said coil discharges, another heating coil in said furnace screened by the first-mentioned coil and receiving vapors from the distillation chamber, an enlarged passageway into which the last-mentioned coil discharges, means for maintaining the temperature in the enlarged passageway without substantial decline, a vapor line leading from said enlarged passageway, a rectifier for the vapors, and means for returning condensate into the top of the rectifier.

4. In apparatus of the character described, the combination of a heating coil located as a screen to absorb radiant heat, a distillation chamber into which said coil discharges, another heating coil screened by the first-mentioned coil and receiving vapors from the distillation chamber, an enlarged passageway into which the last-mentioned coil discharges, means for maintaining the temperature in the enlarged passageway without substantial decline, and means for rectifying vapors from said enlarged passageway.

5. In apparatus of the character described, the combination of a heating coil located as a screen to absorb radiant heat, a distillation chamber into which said coil discharges, another heating coil screened by the first-mentioned coil and receiving vapors from the distillation chamber, an enlarged passageway into which the last-mentioned coil discharges, and means for maintaining the temperature in the enlarged passageway without substantial decline.

6. In apparatus of the character described, the combination of a heating coil located as a screen to absorb radiant heat, a distillation chamber into which said coil discharges, another heating coil screened solely by the first-

mentioned coil, and a vapor line from the chamber to the last-mentioned heating coil.

7. In apparatus of the character described, the combination of a furnace, a heating coil arranged to receive radiant heat from the furnace, a cracking passageway shielded from radiant heat solely by said coil, means for

separating asphaltic substances from the hydrocarbon material which has traversed the heating coil, and means for passing vapors ¹⁰ from the separating means to the cracking passageway.

FRANK A. HOWARD.
